SHOE REPAIR PRESS

Ivie H. Rennie, West Medford, and Harold A. Williams, Wakefield, Mass., assignors to The B. F. Goodrich Company, New York, N. Y., a corporation of New York

Application May 9, 1939, Serial No. 272,570

2 Claims. (Cl. 12—33)

This invention relates to shoe repair presses. The press is especially useful in making "invisible" shoe repairs.

It has been found that the soles of shoes may be repaired by cementing a new piece of sole leather to an old sole using a cellulosic quick-drying cement. After the seam has been cemented and clamped until the cement is dry, the sole is buffed so that the seam is substantially invisible. A half sole may be joined by this method to the shank of an old sole. The sole may then be sewed in place. The press of the present invention is useful in carrying out this method which is known as "invisible repairing."

The principal objects of the invention are to provide simplicity of construction, efficiency of operation, universal adaptability, and low cost of manufacture.

Other objects are to provide reversibility of the press elements, and to provide for performing "invisible" cemented repairs on any part of the sole of a shoe.

These and other objects will appear from the following description and the accompanying drawing.

Of the drawing—

Fig. 1 is a perspective view of the press, one of the pressure screw actuating wheels being broken away.

Fig. 2 is a cross sectional view of the essential parts of the press in use showing a lady's shoe in place therein.

Fig. 3 is a similar view of the press showing a man's shoe in place therein.

Fig. 4 is a similar view showing a lady's shoe therein as used for pressing the toe portion of a shoe.

Referring to the drawing, the numeral 10 designates a bed plate having an integral standard 11 midway thereof and divided at its upper end to provide a pair of oppositely extending arms 12, 13 terminating in threaded bosses 14, 15 for receiving a pair of clamp screws 16, 17 each of which is vertically aligned over a portion of the bed plate. Below the respective clamp screws, the bed plate is arranged to adjustably receive any one of a series of pressing elements. For this purpose the portions of the bed plate below the screws are horizontally extended as at 18, 19 and have guide channels 20, 21 formed therein for centering the pressing elements in one direction. Hand wheels 22 are fixed to the clamp screws to raise or lower the screws for the purpose of releasing or applying pressure to a shoe mounted between the pressing elements.

One of the pressing elements 23 comprises a rectangular base 24 of such width as slidably to fit the channels 20, 21. Near one end thereof it is formed with a pedestal 25 terminating in a horn 26 parallel to its base. The clamping face of the horn extends along the pedestal parallel to the base and merges with a curved portion 26a which joins a surface 26b perpendicular to the base. The arrangement is such that shoes may be adjusted over the horn portion of the pressing element while the element is adjusted along the channel 20 to utilize various portions of the clamping face as shown in Fig. 3, where the curved portion 26a of the face is being used to press the ball portion of the sole of a man's shoe 27, and in Fig. 4 where the straight portion is being used to press the toe of a lady's shoe 28.

The same pressing element 23 may be used in a reversed position, as in Fig. 2 where the clamp screw 16 impinges against the base 24 of the pressing element and the horn 26 of the pressing element is inserted within the shoe 28. The reversible pressing element may be used in a variety of ways in conjunction with other pressing elements and resilient pads.

In Fig. 2 the reversible pressing element is being used to cement a half sole to a lady's shoe including the instep thereof. A pressing element or anvil block 29 conforming in shape over its upper face approximately to the sole and instep of the shoe and having a portion on its lower face adapted to fit the channel 20 is mounted on the base plate of the press. A thick cushion pad 30 of resilient rubber is laid thereover and the shoe 28 is supported thereon. A pad 31 of resilient rubber is placed inside the shoe, and over this the horn of the pressing element 23. Pressure is applied by the screw 16 until the cement has set. The curved portion 26a of the horn makes possible the application of pressure along the instep and the flat horn portion applies pressure along the sole.

Where a repair is to be made by cementing a portion near the toe of a shoe, the parts are arranged as in Fig. 4, where a pressure element 32 and a resilient rubber pad 33 are applied over the sole of the shoe, which is supported by the pressing element 23, and a pad 34 of resilient rubber thereover. The pressing element 23 is moved to the right (in Fig. 4) along the channel 20 to bring the pressure screw 16 over the toe of the shoe. In this position, the rib 32a of the pressing element 32, which rib is adapted to be received in channels 20, 21 when the pressing element is

used adjacent the base, is engaged by the screw 17 for applying pressure to the sole.

When the shank of a shoe is to be repaired, the parts may be arranged as in Fig. 3, a pressure element 32 and resilient pad 33 being applied over the shank of the shoe which is supported on the horn of the pressure element 23 and a resilient pad 34 of rubber, the pressure element 23 however is moved along the channel 20 to a position where its curved portion 26a is below the pressure screw 16.

The reversibility of the pressure element 23 substantially reduces the number of pressure elements required and permits a great variation in the tasks to be performed.

While the apparatus has been described as a dual clamping apparatus adapted to press a pair of shoes at one time, the features of the invention may also be employed in a single-armed press.

These and other variations may be made without departing from the invention as it is defined by the following claims.

We claim:

1. A press for use in repairing footwear, said press comprising a bed having a guideway thereon for adjustably supporting interchangeable pressing elements, an arm opposed to said bed, pressure applying means supported by said arm, and a pair of pressing elements removably mounted between said bed and said arm for en-

gaging a shoe therebetween, said pressing elements each being adapted and arranged to be positioned optionally against said bed or said pressure means, and said pressing elements each having means for engagement of the element with said guideway when positioned in contact with said bed for adjustment therewith while the other element is engaged by said pressure applying means.

2. A press for use in repairing footwear, said press comprising a bed having a guideway thereon for adjustably supporting interchangeable pressing elements, an arm opposed to said bed, pressure means supported by said arm, and a pair of pressing elements removably mounted between said bed and said arm for engaging a shoe therebetween, said pressing elements each being adapted and arranged to be positioned against said bed or said pressure means, said pressing elements each having means for engagement of the element with said guideway when positioned in contact with said bed for adjustment therewith, while the other element is engaged by said pressure applying means, and one of said pressing elements comprising a base adapted to engage said guideway, a pedestal projecting from said base and having a sole-pressing horn and a curved shank-pressing portion at the root of said horn.
